UNITED STATES PATENT OFFICE.

HENRI FRANCOIS ETIENNE SYLVAIN DUSSERIS, OF PARIS, FRANCE.

APPARATUS FOR MOVABLE PUBLICITY.

Application filed April 22, 1924. Serial No. 708,287.

To all whom it may concern:

Be it known that I, HENRI FRANCOIS ETIENNE SYLVAIN DUSSERIS, a citizen of France, and a resident of Paris, France, **5** have invented some new and useful Improvements in Apparatus for Movable Publicity, of which the following is a specification.

This invention relates to apparatus for **10** movable publicity and its object is to provide more especially improvements in apparatus described in the Patent No. 1,456,124.

The apparatus described in said Letters **15** Patent consists mainly of the movable endless element such as a chain Vaucanson or Galle or a roller chain, and of a means destined to support the advertisements on said endless element. This means consisted of a **20** cross-bar passing through a kind of sheath and attached, with aid of special hooks or the like by their extremities to the links of the parallel chains constituting the movable element.

25 In practical use of the apparatus such as described in said Letters Patent the experience proved that the roller chain (cycle chain) suits particularly well the purpose in view, as movable element, but that the **30** utilization of hooks of the kind described for the fixation of the crossbars on said chains did not prove entirely satisfactory.

The employment of said hooks fixed by simple hooking on necessitates the use of a **35** small sleeve destined to be pushed over the loop in order to avoid the detachment of the chain; this means of establishing connection between the crossbar and the chain was not sufficiently rigid; especially in the case **40** of unrolling the advertisements in a horizontal sense (rather than in the vertical one-case of said Letters Patent) the rigidity in the crossbars was not sufficient to maintain a constant distance between the chains, these **45** chains tending to inflect owing to their own weight.

The present invention provides means avoiding this drawback, and simplifies at the same time the manufacture of the means **50** serving for attachment of the crossbars to the chains.

These means consist in axles mounted on each chain opposite to each other. These axles are prolonged in the direction of the

crossbar by a hollow portion receiving the **55** corresponding extremity of the crossbar supported in this manner as by bearings.

In the annexed drawings:

Figures 1 and 2 represent one of the axles in elevation and in a sectional view, these **60** axles cooperating in the mounting of a crossbar on the chains.

Figure 3 shows the manner of application of said axles to a crossbar supporting an advertisement and fixing the two chains form- **65** ing a movable element.

In order to apply the specified attachment means it is necessary to remove the rivets from the chain links at the points chosen for the fixation of the crossbars 4. Instead **70** of these rivets a simple axle 1 is mounted into the chain and maintained by a nut 2; the hollow portion 3 of said axle is directed toward the advertisement in order to receive the extremity 5 of the crossbar **75** 4.

On the other chain, opposite the axle 1 of the preceding chain, a similar axle 1 is mounted, the hollow portion 3 of the same being directed, equally, against the advertisement. In order to mount the crossbar **80** 4 between the axles 1 forming the attachment means, first one extremity of the crossbar engages the hollow corresponding portion 3 of the axle, and thereupon the other extremity is brought to engage the hollow portion **85** of the corresponding axle, the chains being kept meanwhile at a distance from each other, as necessary for the introduction of the considered extremity.

The chains returning to their position offer **90** a sufficient tension for maintaining the axles against the extremities of the crossbar.

If the chains at disposal are those with **95** dismountable links, it will be easy for any person to perform the necessary transformations for advertisements carried by chains; to augment or to diminish this surface, according to the engravings or prints destined to appear as advertisements. It will be sufficient for this purpose to substitute the described hollow axles for the dismountable axles or rivets of the chain links and to place therein the crossbar carrying its advertisement as described in said Letters Patent.

What I claim is:—

In advertising apparatus, a pair of spaced chains, a cross bar between the chains, of less length than the width of the space be-

tween the chains, and provided with cylindrical extremities, axle members extending through openings in certain of the chain links and pivotally connecting said links together, said axle members having diametrically enlarged inner portions extending toward each other from the opposing sides

of the chains and provided with bores in which the said extremities of said cross bars are fitted, and nuts screwed on said axle members and bearing against the outer sides of the chains.

In witness whereof I affix my signature.
HENRI FRANÇOIS ETIENNE SYLVAIN DUSSERIS.
